UNITED STATES PATENT OFFICE.

ANDREAS K. HOLTE, OF CHICAGO, ILLINOIS.

IMPROVEMENT IN FIRE-PROOF BUILDINGS.

Specification forming part of Letters Patent No. 136,515, dated March 4, 1873.

To all whom it may concern:

Be it known that I, ANDREAS K. HOLTE, residing at Chicago, in the county of Cook and State of Illinois, have invented a certain Improvement in Fire-Proof Buildings, of which the following is a specification:

The nature of my invention consists in constructing all buildings with roofs composed of arches of brick, and covering the exterior walls and such arched roof with a layer of proper thickness of clay upon the outside, so that the building may be able to withstand the heat of burning buildings around it, the construction of the roof affording a safeguard against being crushed in by falling *débris*. The layer of clay is, in turn, coated with hydraulic cement, or other equivalent material capable of resisting the influence of the weather.

Figure 1 represents a front elevation of a building constructed according to my invention. Fig. 2 is a sectional plan view of part of a frame building with a thin exterior brick wall. Fig. 3 is a transverse vertical section in a plane indicated by the line *x x* of Fig. 2, showing the manner of constructing a light arched roof and of building a floor fire-proof. Figs. 4 and 5 are views of fire-proof shutters and doors such as I prefer to employ.

The same letters of reference are employed in all the figures in the designation of identical parts.

Buildings constructed of brick or stone are provided or covered with an arched roof of brick, say nine inches in thickness, and both the exterior walls and the roof are plastered upon the outside with a layer of clay, *a*, which may vary in thickness from one-half of an inch to one inch, and may be mixed with a small proportion of glue to give it sufficient adhesiveness. This layer of clay, when perfectly dry, is coated with cement *b*, or other suitable material not easily affected by the influence of the weather, and may finally be whitewashed or painted. Frame buildings are made without the outside weather-boarding, instead of which the frame-work is jacketed in a thin brick wall, as shown in Fig. 2, where *A* represents the light brick wall; *B*, the uprights; and *C*, an inside covering of board or laths, plastered in the ordinary manner.

The space between the outside brick wall and the inside lining may be filled with clay between the uprights, to add to the strength and durability of the wall. Frame houses and other houses built too frail for the support of a nine-inch brick arched roof may be covered by a four-and-a-half-inch brick arch, strengthened by an interior frame-work of wood or iron, in the manner illustrated in Fig. 3. All permanent wood-work of the building, whether upon the exterior or interior thereof, should be covered with a thin coat of clay, in manner like the walls and roof, to resist the influence of the heat of a fire. The floors may be built as shown in Fig. 3, where the upper part of the joists is embedded in clay *I*, supported upon boards *H*, and covered by the ordinary floor-boards *K*.

The lower part of the joists is covered with a thick layer of plaster. The window-shutters and doors are all made of fire-proof construction, either by using iron or making them of wood, ribbed, and jacketed with a coat of clay, as indicated in Figs. 4 and 5, *F* representing the wooden door or shutter; *E*, the ribs thereon; and *D*, the coat of clay.

Where ordinary doors are used, additional fire-proof ones are provided, sliding in recesses in the wall, as shown in Fig. 2, so that should a fire occur in any one room in the house it may be confined to such room by closing it up tight. The top of the chimney should also be provided with a metal damper to shut off the draft through it in case of a fire in the building.

What I claim as my invention, and desire to secure by Letters Patent, is—

A building constructed with an arched roof of brick, and having the exterior of its brick or stone walls and such roof covered with a layer of clay, which is, in turn, coated with hydraulic cement or its equivalent, substantially as and for the purpose specified.

In testimony whereof I have signed my name to this specification in the presence of two subscribing witnesses.

ANDREAS K. HOLTE.
